John E. Earle

United States Patent Office.

MARY ANN BOUGHTON, OF BRIDGEPORT, CONNECTICUT.

Letters Patent No. 113,842, dated April 18, 1871.

IMPROVEMENT IN COOKING-STOVES.

The Schedule referred to in these Letters Patent and making part of the same.

To all whom it may concern:

Be it known that I, MARY ANN BOUGHTON, of Bridgeport, in the county of Fairfield and State of Connecticut, have invented a new Improvement in Cooking-Stoves; and I do hereby declare the following, when taken in connection with the accompanying drawings and the letters of reference marked thereon, to be a full, clear, and exact description of the same, and which said drawings constitute part of this specification, and represent in—

Figure 1, a perspective view from the rear of the stove;

Figure 2, a sectional view on line xx of fig. 3.

Figure 3, a vertical section on line yy of fig. 2; and in

Figure 4, a sectional view of the outlet-pipe, to illustrate the arrangement of the dampers.

This invention relates to an improvement in common cooking-stoves, and consists in the arrangement of a shelf upon the rear of the stove, so as to be turned up against the stove when not in use, or down when required for use.

In the accompanying drawings—

A, is the top of the stove;

B, the fire-box;

C, the oven; and

D, the outlet.

From the fire-box over the top of the oven is arranged a plate, a , which covers the oven, and is joined

to the plate d , which forms the back of the oven thence around to the plate f , which forms the bottom of the oven, thence to the tubes or pipes, or other flues, g , which conduct to a passage, h , between the plate a and top i of the oven, and this passage or flue h opens into the outlet-pipe D.

Dampers, n and m , are arranged in the said outlet-pipe, so that when pushed down, as seen at n , fig. 4, the connection with the passage h is closed and communication is open to the outlet directly from the fire; or when raised, as denoted at m , the opening from the fire directly is cut off and the passage h to the outlet opened.

Upon the back of the stove I hinge a plate or shelf, E, so as to be dropped to the position denoted in blue, and there self-supporting; or turned up, as denoted in black, and there held in any convenient manner; the object of the shelf being to afford a convenient position for the placing of articles desired to be kept in a warm state.

Having thus fully described my invention,

What I claim as new and useful, and desire to secure by Letters Patent, is—

The arrangement of the hinged shelf E in the rear of the stove, as and for the purpose specified.

MARY ANN BOUGHTON.
